(57) **CLAIM**

The ornamental design for a strap of an eyemask as shown and described.

DESCRIPTION

FIG. 1 is a perspective view of a strap of an eyemask showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The evenly dashed broken lines illustrate portions of the article that form no part of the claimed design. The unevenly dashed broken lines show boundaries of the claimed design and form no part thereof. The cross-hatched broken lines in FIGS. 1 and 2 show portions of the article, and form no part of the claimed design.
